ABSTRACT OF THE DISCLOSURE

A lamp is exhausted, filled and sealed with an extra length of exhaust tube attached to the lamp envelope. The lamp is then heated and a D.C. potential applied between the exhaust tube and a lead-in wire, whereby the contaminating alkali metals are attracted to the exhaust tube and deposited therein. The lamp is then tipped off adjacent to the envelope and the exhaust tube, containing the contaminating metal deposit, is discarded.

Background of the invention

This invention pertains to electric lamps and the like and to their manufacture. It particularly relates to lamps in which the envelope is made of high-silica glass and the fill comprises halogen and an inert gas. The filament normally operates at a higher temperature than does that of conventional incandescent lamps and is, therefore, affected more by contaminating alkali metals.

Lamps of this type contain traces of alkali metal contaminants such as sodium, lithium and potassium in the lamp envelope, the tungsten filament and the lead-in wires. In operation, these contaminants can combine with the halogen fill to form gaseous compounds. In the region of the hot filament, the molecules of these compounds appear to dissociate and form ions of the alkali metals. The voltage gradient that exists between the ends of the filament influences and accelerates the ions, resulting in gaseous ionization current flowing between the ends of the filament. This phenomenon is known as "current-creep." As the gaseous ionization current gradually increases to a critical limit, it results in an arc which melts the ends of the filament and causes premature failure of the lamp.

Summary

This invention discloses a novel process for substantially eliminating premature lamp failures resulting from "current-creep" by considerably reducing the amount of alkali metal contamination within the lamp. Since the amount needed to cause the above-mentioned gaseous ionization current is very small, in the order of fractions of a microgram, it is neither economically feasible nor sufficient to merely remove the alkali from the components prior to manufacture of the lamp. For example, the high-silica glass used in the lamp envelope normally contains about 5 to 100 parts per million of alkali metal impurities and the tungsten filament contains about 10 to 200 parts per million. Therefore, for an envelope weighing about 3 grams and a filament weighing about 0.5 gram, the total alkali impurity can vary from about 20 to 400 micrograms and it would be prohibitively expensive to purify the components to a total impurity of less than about 1 microgram. It is also likely that contaminating alkali is introduced into the lamp during the manufacturing process from, for example, the apparatus used in positioning and welding the filament on the support or from the equipment used in sealing the lead-in wires in the high silica glass.

2

In my new process, the alkali contaminant is attracted to and deposited on a part of the lamp where it can be easily removed, such as a lengthened exhaust tube. Specifically, the lamp is heated until the alkali metals are thermally ionized and, by means of a D.C. potential, are attracted to the exhaust tube. The lamp is then tipped off adjacent to the envelope and the exhaust tube, which now contains the alkali contaminants, is discarded. Thus the alkali contaminants are reduced sufficiently so that failures due to "current-creep" caused by the alkali ions are substantially eliminated.

Brief description of the drawing

FIGURES 1 and 2 are elevational views of a lamp as it is processed in accordance with this invention.

FIGURE 3 is an elevational view of a finished lamp.

Description of the preferred embodiments

In FIGURE 1 a lamp is shown which has been out-gassed, flushed, filled with an inert gas and halogen, and sealed at tip 1 of exhaust tube 2. The exhaust tube is attached to envelope 3 and is long enough to provide for the subsequent steps of the invention. A metal clip 4 is disposed around a portion 12 of exhaust tube 2 adjacent to envelope 3 and is connected to the negative terminal 15 of a D.C. supply 6. One of the external lead-in wires 7 is connected to the positive terminal 8 of D.C. supply 6. The lead-in wires 7 are connected to internal lead-in wires 14 and the filament 9 through seal 10. With filament 9 energized to light the lamp, a D.C. potential is applied between metal clip 4 and lead-in wire 7 which effectively establishes the potential between tube portion 12 and filament 9. Subsequently, the process is discontinued and metal clip 4 is removed. A discoloration 16, usually brown or yellow, is apparent in tube portion 12.

As shown in FIGURE 2, the lamp is then tipped off between tube portion 12 and envelope 3, for example, by heat-sealing in a manner usual in the art, without exposing the internal fill gas in envelope 3 to the atmosphere, and the contaminant-containing exhaust tube 2, after being thus detached from lamp envelope 3, is discarded. The finished lamp now sealed by tip 13 is shown in FIGURE 3.

The source of the alkali metal contaminant can be lamp envelope 3, filament 9 and internal lead-in wires 14 in addition to the previously-mentioned processing equipment. Lamp envelope 3 is usually made of high-silica glass and, inherently, contains trace quantities of alkali metal including sodium, potassium and lithium varying from about 5 to 100 parts per million. Filament 9 and internal lead-in wires 14 are usually made of tungsten and contain about 5 to 100 parts per million of alkali metal. Within a lamp which has been processed and sealed, but not yet electrolyzed by my process, the alkali can exist in the gaseous fill, on the surface of the lamp parts and in solution in the lamp parts. It is probable that the reaction

where A is the alkali metal and H is the halogen, indicates the mechanism by which the alkali is removed. When the negative D.C. potential is applied to the outer surface of tube portion 12, the positive alkali ions on its inside surface are attracted to the outside, leaving the inside surface deficient in alkali ions. The alkali halide molecules in the gas coming into contact with this surface are dissociated, according to reaction 1, and the alkali ions are removed as rapidly as they are formed by dissolving in the silica glass and being attracted toward metal clip 4. The negative halide ions travel toward positive filament 9 and are discharged there. As the alkali halide content of the gas is progressively reduced, the alkali ions on all

other inside surfaces of the lamp react with the halogen fill to form alkali halide molecules, according to reaction 1. These molecules continue to diffuse toward tube portion 12 where the alkali continues to be removed. As the alkali ions on the inside surfaces are removed, the more deeply embedded ions in solution migrate toward the surface and continue the depletion process. It is usually not necessary to continue the electrolyzing process beyond the point where a spectrometric analysis of the gas content of the lamp does not detect any alkali metal.

In the specific example of a 650 watt, 120 volt, T4 lamp a microammeter 15 was installed in the circuit to measure the electrolysis current and spectrometric techniques were used to measure the amount of alkali impurity in the gas phase of the lamp. The limit of detectability of alkali by this technique appeared to be about 2.1×10^{-10} moles. When this lamp was operated at its rated voltage and 750 volts D.C. applied between clip 4 and one of lead-in wires 7, a D.C. current of positive ions was drawn outward through the silica of from 3 to 30 microamperes. This current would rapidly decrease and a concurrent measurement of the alkali in the gas phase of the lamp showed a similar decrease. When the detectability limit of alkali was reached, there was still a small amount of current flow as indicated by the microammeter, probably due in part to a leakage current in the quartz itself. In eight lamps tested the total quantity of electrolyzed alkali which had to be removed from each lamp to reduce it below the detectability limit of about 2.1×10^{-10} moles was equivalent to between 7.5 and 12 microampere-minutes of ionization current. It is estimated that this is equivalent to a transport of about 5.4 to 8.6×10^{-9} moles of alkali.

The reason that the electrolysis current is initially high in this process is probably due to the alkali contaminants initially present in the gas phase and on the inside lamp surfaces, which are rapidly removed and deposited in exhaust tube portion 12. Contaminants more deeply in solution in the lamp parts or on cooler portions of the lamp are removed at a slower rate, in accordance with reaction 1, and the electrolysis current correspondingly decreases.

The amount of alkali removed in order to eliminate current-creep failures was small compared to the inherent impurities in the silica and tungsten. In the example of the 650 watt lamp, the 5.4 to 8.6×10^{-9} moles of alkali removed is equivalent to 0.12 to 0.2 microgram of sodium. The silica envelope weighed 2.2 grams and the tungsten filament weighed 0.475 gram. At alkali impurity levels of approximately 8 and 40 parts per million respectively, this equals 17.2 and 19 micrograms of alkali impurity. However, a large proportion of this alkali was volatilized and removed by the high temperatures during sealing, filament light-up and outgassing and some of it was deposited on the cooler parts of the lamp where it could eventually contribute to the current-creep problem is not removed by electrolysis.

In another test on a series of lamps where the sodium content of the gas was spectroscopically measured, the average content was 0.13 microgram initially and less than .003 microgram after electrolysis. Between 0.3 and 1.5 micrograms of sodium were removed from each lamp. During life testing, none of these lamps showed any evidence of current-creep. By contrast, similar lamps made without the electrolysis treatment showed an increase in the average sodium content of the gas to 0.26 microgram after a few hours of life testing. Tests have shown that a gas sodium content of about 0.3 to 0.4 microgram will result in arc failure of the lamp when it is operated at its rated voltage.

The rate of removal of the contaminating alkali metals can be increased by operating the lamp at a higher temperature, such as at 110% of its rated voltage, during the electrolysis process, or by increasing the D.C. potential to about 1500 volts. Electrolysis currents of up to 400 microamperes have been measured at these conditions.

The significant improvement in lamp life resulting from

this invention is illustrated by a comparison test of a T4 single-end, high-silica glass, bromine and argon filled lamp, which is life rated for 25 hours at 120 volts. The electrolyzed lamps had an average life of 39 hours, as against 3.8 hours for those not electrolyzed.

Individual spectrometric measurements of the content of sodium, potassium and lithium in the gas during the electrolyzing process showed decreases in the amount measured that corresponded with the decrease in the ionization current. On the T4 lamp, electrolyzed at 750 volts D.C. while the lamp was operated at 120 volts, all three alkali metals were removed to undetectable amounts within in three minutes.

Although only the preferred embodiment has been described, the essence of my invention is the application of the D.C. potential between two parts of a lamp whereby the alkali contaminants are attracted to the negative part and can be effectively removed from contributing to the ionization current or current-creep that can occur during the life of the lamp. It is apparent that the negative part of the lamp need not be the exhaust tube but can be any part capable of removal without detriment to the lamp. Other tests have indicated that the contaminants need not even be removed from the lamp but can be deposited on a relatively cool portion where the temperature during operation is insufficient to result in their thermal ionization. This feature would be dependent on the size of the lamp envelope, the filament temperature, the fill pressure and other lamp characteristics. As indicated above, the rate of removal of the alkali contaminants from the lamp during electrolysis is dependent on the D.C. potential and the temperature to which it is subjected. On the T4 lamp, the envelope temperature is about 750 to 850° C. when the lamp is operated at its rated 120 volts. When the envelope temperature is increased, either by external means or by operating the filament at higher than 120 volts, the rate of removal is also increased. The maximum temperature is limited by the melting point of the high-silica glass envelope, about 1500° C. Below about 500° C., it is estimated the rate of removal is too slow to be practical.

It is apparent that modifications and changes can be made within the spirit and scope of the instant invention, but it is my intention to be limited only by the appended claims.

What I claim is:

1. In the manufacture of an electric lamp, the steps for removing trace amounts of alkali metal impurities which comprise:

applying a negative D.C. potential to a detachable part of the lamp envelope, whereby said alkali metal impurities are attracted to said detachable part; and detaching said detachable part containing said impurities from said lamp envelope.

2. The process according to claim 1 wherein said detachable part is the exhaust tube.

3. The process according to claim 2 wherein said lamp is heated while said D.C. potential is applied.

4. In the manufacture of an electric lamp the steps for removing trace amounts of alkali metal impurities which comprise:

heating said lamp;

applying a D.C. potential between a lead-in wire and a portion of the exhaust tube of said lamp, said portion to which said D.C. potential is applied being negative, whereby said alkali metal impurities are attracted to said portion; detaching said portion containing said impurities from said lamp.

5. The process according to claim 1 wherein said heat is generated by lighting said lamp.

6. The process according to claim 2 wherein said lamp is filled with a halogen and an inert gas.

7. In the manufacture of an electric lamp containing a gaseous fill including halogen, the steps for removing

trace amounts of alkali metal impurities which comprise:
disposing a metal conductor around the exhaust tube of
a lamp envelope;
lighting said lamp;
applying a D.C. potential between said conductor and
a lead-in wire of said lamp, said conductor being
negative, whereby said alkali metal impurities are
ionized and attracted to said exhaust tube and are
therein collected;
sealing said exhaust tube between said conductor and
said lamp envelope and detaching said exhaust tube
wherein said alkali metal impurities are collected.
8. In the manufacture of an electric lamp containing
trace amounts of alkali metal impurities, the steps which
comprise:

heating said lamp;
applying a negative D.C. potential to a part of the
envelope of said lamp, whereby said impurities are
attracted to said part of said envelope;
the temperature of said part of said envelope, during
normal operation of said lamp, not exceeding that at
which thermal ionization of said alkali metal im-
purities occurs.
